(57) **CLAIM**

The ornamental design for a switch housing for a perforating gun assembly, as shown and described.

DESCRIPTION

FIG. 1 is a first perspective view of a switch housing, showing our new design.

FIG. 2 is second perspective view of the switch housing of FIG. 1, shown from a different angle.

FIG. 3 is a front plan view of the switch housing of FIG. 1.

FIG. 4 is a rear plan view thereof.

FIG. 5 is a top plan view thereof.

FIG. 6 is a bottom plan view thereof.

FIG. 7 is a right side elevation view thereof; and,

FIG. 8 is a left side elevation view thereof.

The broken lines in the drawings depict portions of the switch housing that form no part of the claimed designs.

1 Claim, 4 Drawing Sheets
